2 SHEETS—SHEET 2.

UNITED STATES PATENT OFFICE.

JAMES M. HAWTHORNE, OF HAVACO, WEST VIRGINIA.

SAFETY CLUTCH FOR ELEVATORS.

Application filed September 29, 1921. Serial No. 504,016.

To all whom it may concern:

Be it known that I, JAMES M. HAWTHORNE, a citizen of the United States, residing at Havaco, in the county of McDowell and State of West Virginia, have invented certain new and useful Improvements in Safety Clutches for Elevators; and I do hereby declare the following to be a full, clear, and exact description of the invention, such as will enable others skilled in the art to which it appertains to make and use the same.

This invention relates to a safety clutch mechanism for elevators generally but particularly for mine cages.

An important object is to provide means to efficiently replace the wooden guides used so as to overcome the frequent repair and adjustment required, and to provide a construction of metal, preferably steel, which will cooperate with latching mechanism possessing the novelty which will appear from a consideration of the description following taken in connection with accompanying drawings of one preferred embodiment.

In said drawings:—

Figure 1 is a front elevation of an elevator or mine cage constructed in accordance with my invention;

Figure 2 is a view substantially similar to Figure 1 but with the latch rails partly in section, and the safety clutch mechanism applied;

Figure 3 is a central vertical sectional view taken transversely of the cage and on the line 3—3 of Figure 1; and

Figures 4 and 5 are detail transverse sectional views taken on the lines 4—4 and 5—5 respectively, of Figure 1.

Like reference characters designate like or similar parts throughout the views of the drawings.

In reducing the invention to practice, a suitable frame work is provided which may consist of uprights 6, disposed in spaced pairs at each side of the apparatus, maintained in such relation by connecting bars 7 and the pairs being connected together by horizontal base and top bars 8, on which bars 7 adjacent to the bars 8 may rest. Said framework may be made of wood or metal as desired and the details thereof may be varied in any preferred manner.

Secured to the bars 7 and disposed vertically, are track rails 9, which are generally of U-shape in cross section so as to provide in-

clined rack teeth 10 at the base of a groove having the sides defined by the flanges extending outwardly and beyond the operative faces of the teeth 11. These rack rails 9 are preferably made from metal like steel in order to be very durable in use, and to replace wooden rack rails such as are generally used and which require constant repair at great expense. The rails 9 may be secured in place in any suitable manner, for instance by means of flanges 12 riveted thereto or otherwise secured as at 13, and bolted, as at 14, to the bars 7.

The elevator or cage is generally shown 70 at A. Said cage may have stiles 15, one at each side to slide on the free edges of the flanges 11, which are connected at their bottom with a base bar 16 and adjacent the tops by base side bars 17 and 18 secured thereto 75 at 19 and which overlap rails 9. Secured to the stiles 15 as at 20 or formed integral therewith as preferred, are retaining strips 21 which overlap the rails 9. Strips 21 depend at their lower ends across the base bar 80 16 as shown.

Secured against the interior of the bars 17 and 18 are angle iron track members 22, which mount clutch or latch plates or blocks 23 for horizontal sliding movement. Clutch 85 blocks 23 are toothed adjacent the teeth 10 to conform in shape thereto. Said clutch blocks 23 slide through and are retained in slots 24 provided in the upper end of stiles 15. Links 25 are pivoted at 26 to the clutch 90 blocks 23 and at 27 to a head block 28.

Removably passable through block 28 is a rod 29 having a plurality of apertures therethrough as at 30 and through a selected pair of which removable pins 31 are passed to 95 engage the upper and lower edges of the block 28 in order to secure the rods 30 thereto against movement vertically independently thereof. Said rod 30 slides through an opening to a plate 33 secured in the bars 100 18 and an extensible coil spring 34 surrounds said rod 30 below plates 33 and a removable pin 35 extends through one of the apertures 31 so that the lower end of the spring 34 may rest thereon and be secured 105 in place. As said spring 34 is expansive, its tendency is to draw the head 28 forwardly into contact with the plate 33 and thus by means of the links 25 slide the clutch blocks 23 into engagement with the teeth 10. 110

The hoisting cable for the cage or elevator is shown at 36 and is secured to a retainer

block 37, pivoted at 38, to an eyelet 39 integral or otherwise rigid with the rod 29.

In use, the cable 36 due to its tension elevates the retainer 37, rod 29; and accordingly the head 28. Such elevation of the head 28 inclines the links 25 which slidably retracts the clutch blocks 23 maintaining their teeth out of engagement with the rack teeth 10. Thus the cage or elevator is free to slide. In such position, however, the spring 34 is tensioned so that in the event the cable 36 breaks, said spring through its abutment with the pin 35, depresses rod 29, causing the head 28 to lower, straightening the links 25 and urging the clutch blocks 23 at their teeth into locked or clutched relation with the teeth 10, thus arresting descent or ascent of the elevator.

Due to the fact that the rails 9 are made of metal, they will prove very durable in use and overcome the present objection to wooden rails.

Attention is called to the fact that the links 25 are disposed between the planes of the bars 17 and 18, so that said bars will overlap the links and substantially snugly retain the same and the clutch plates 23, in order to relieve them as well as the head 28, of undue lateral strain.

30 I claim as my invention:—

1. An elevator safety clutch mechanism comprising track rails having teeth, stiles disposed over said rails having openings therethrough, clutch members slidably through said openings, bars secured to said stiles and overlapping said rails, guide means for the clutch members on and intermediate said bars, a head, links pivoted to

said clutch members and to said head disposed intermediate the bars and clutch members and overlapped by the bars, a rod insertable through said head, said rod having a plurality of openings, means passing through selected openings to secure the rod to the head against vertical movement independent thereof, a hoisting cable, means to secure said cable on the rod, a plate secured to and intermediate said bars, said rod being slidable through said plate and extending below it, a pin extending through one of said openings of the rod below said plate, and an expansive spring surrounding said rod and abutting said last mentioned pin at one end and said plate at the other end.

2. An elevator safety catch mechanism including a track rail having teeth and spaced sides extending outwardly beyond said teeth, an elevator stile disposed across the free edges of said sides and having a slot therethrough, a clutch member slidable through said slot and engageable and disengageable with said teeth, track members for said clutch member extending from the stile, retaining strips overlapping the stile, track members and said sides, elevator suspending means, and means to normally maintain the clutch member retracted and for release upon breakage of the elevator suspending means.

In testimony whereof I affix my signature 70 in presence of two witnesses.

JAMES M. HAWTHORNE.
